WALL COPING

Martin S. Bowne, Clearfield, Ky., assignor to Lee
Clay Products Company, Inc., Clearfield, Ky.

Application October 16, 1940, Serial No. 361,453

10 Claims. (Cl. 72—86)

The present invention relates to wall coping of the type comprising sections adapted to be arranged along the top of a wall so as to provide a covering thereon. More specifically the invention pertains to a wall coping wherein means is provided for closing the joints between the sections including means for preventing moisture which may inadvertently pass through the joints from moving onto the top of the wall.

Wall copings of this general type are usually formed with the coping sections having an outwardly flared formation or tongue at one end of each coping section into which a plain end of each coping section was adapted to fit. Such a coping arrangement was thus provided with a series of spaced projections along the top of the wall. Another wall coping arrangement includes an inwardly flared tongue at one end of each coping section onto which a plain end of each coping section was arranged whereby the top surface of the wall coping was smooth and free of spaced projections at the joints between the coping sections. These prior coping arrangements, however, have not been satisfactory in that moisture has been found to pass through the joints between the coping sections.

An object of the present invention pertains to the provision of means providing leak-proof joints adjacent the abutting ends of the sections of the wall coping without resorting to overlapping projections on the coping sections.

Another object of the invention resides in providing means for laterally draining any moisture leaking through a joint between the adjoining end sections of the wall coping so that the moisture will be conveyed laterally of the wall for discharge along the sides of the wall.

A still further and more specific object of the invention pertains to the provision of a drain member which extends transversely of the wall coping under adjacent ends thereof for conveying moisture which may pass through the joint to points laterally of the wall so that the moisture may fall along the sides thereof without engaging the top of the wall proper.

Other and further features and objects of the invention will be more apparent from a consideration of the following description and the accompanying drawings wherein several exemplary embodiments of the invention are disclosed.

In the drawings:

Fig. 1 is a sectional view of a wall coping section embodying the invention and showing a drain member partly in section, associated with the wall coping.

Fig. 2 is a sectional view of the wall coping and drain member taken on the line II—II of Fig. 1.

Fig. 3 is a similar sectional view taken on the line III—III of Fig. 1.

Fig. 4 is a perspective view of a wall coping section illustrating the plain ends thereof.

Fig. 5 is a perspective view of one form of drain member.

Fig. 6 is a sectional view taken on the line VI—VI of Fig. 7 illustrating a modified arrangement for draining moisture laterally of the wall.

Fig. 7 is a sectional view of a wall coping taken on the line VII—VII of Fig. 6 and showing the drainage member in section.

Referring to the drawings and particularly Fig. 4, there is shown at 10 a wall coping section which may be formed of fired clay and wall coping sections of this general type are often referred to as coping tiles. In carrying out the present invention the top portions of the wall coping sections are formed with depending flanges 11 and 12. These depending flanges are preferably spaced so as to extend downwardly over a wall such as indicated at 14 in Fig. 1. The top portion of the wall sections may be suitably shaped to provide lateral drainage thereon. Thus for example the central portion 16 may be slightly raised to provide for the conduction of moisture laterally towards the edges of the coping.

The under surface of each coping section is preferably flat as indicated at 17.

Each wall coping section 10 is provided with depending ribs 18 and 19 and these ribs may be integrally formed during the moulding of the coping sections. The ribs 18 and 19 are spaced and provided for the purpose of supporting the coping sections on the wall to be covered. The depending ribs 18 and 19 terminate short of the ends of the wall coping sections for purposes hereinafter described. The wall coping sections 10 having a shape as shown in Fig. 4 are arranged along the top of a wall with one of the sections abutting another similar shaped tile wall coping. The ends of each wall coping may be plain or substantially straight as shown in Fig. 4.

The adjacent ends of the coping sections are more clearly shown in Figs. 2 and 3 and each space between the ends of the coping sections is filled with a suitable sealing compound such as plastic material or mortar may be employed as indicated at 21 in Figs. 2 and 3. In a preferred arrangement a plastic material is supplied to the space between the ends of the coping sections so that the sealing material 21 may be forced into the joint by means of a pressure gun.

50

55

In carrying out the invention means is provided for laterally draining any moisture leaking through the joints between adjacent ends of the coping sections. Thus a drain member 20 may be arranged under the adjoining ends of the coping sections and the drain member may be shaped similar to that illustrated in Fig. 5. In this form of the drain member a central rib 22 is provided and adapted to be arranged immediately under the adjoining ends of the coping sections. The drain member 20 is provided with two channels 23 and 24 laterally of the central rib 22. The base portion 26 of the drain member is preferably flat so as to be supported on the wall 14. The drain block is arranged transversely of the wall as illustrated in Fig. 1 and the central rib 22 thus closes the space between the adjoining ends of the coping sections. The central rib 22 provides means for retaining the plastic sealing material 21 in the space between the ends of the wall sections prior to the solidification thereof. The drain member may be provided with a general rectangular shape in cross-section so as to be arranged transversely of the wall and under the adjacent ends of the wall coping sections and lie within the spaces provided by the terminated depending ribs 18 and 19.

The drain member 20 is preferably of a slightly greater length than the width of the wall 14 and of shorter length than the space between the depending flanges 11 and 12. Thus any moisture inadvertently penetrating through the joint between the ends of the coping sections or through the sealing material 21 moves into the channels 23 and 24 as indicated by the arrows in Fig. 3. The drain member 20 may be properly secured to the top of the wall by means of mortar 27 and the drain member may be slightly tilted or sloped to drain the moisture laterally of the wall in the channels 23 and 24 or these channels may slope downwardly from the center of the drain member so that the moisture will be conducted to the sides of the wall as indicated by the arrows in Fig. 1.

A modified arrangement for conducting the moisture which inadvertently penetrates through the joints is shown in Figs. 6 and 7. In this modification the coping sections are provided with integral depending ribs 18a and 19a. The depending ribs in this modification are of the same length as the coping sections and the ribs adjacent the ends of the wall coping sections are provided with recesses 28 as shown in Fig. 6. Each rib is thus provided with a shoulder 29 for supporting a drainage member as hereinafter described.

When the two coping sections are arranged with the ends thereof adjacent each other the space between is filled with a suitable plastic sealing compound 21. Any moisture that may inadvertently penetrate through the sealing material 21 is conducted laterally of the wall 14 by means of a drain member 31 which may be formed of sheet material such as copper. The drain member 31 when viewed in section is provided with a flat bottom portion and upward extending flanges 32 and 33. These flanges 32 and 33 may be formed integrally with the base portion of the drain member. The sheet metal drain member 31 is arranged transversely of the wall and is adapted to fit within the recesses 28 provided in the ends of the depending ribs 18a and 19a.

In actual practice it may be preferable to arrange the drain member 31 in a proper posi-

tion under the space between the adjacent ends of the wall coping sections and thereafter fill the joint space with the plastic sealing material 21. The plastic sealing material may therefore extend downwardly into the drainage member between the flanges 32 and 33. Any moisture penetrating through the joint or the sealing compound 21 is conducted laterally of the wall by means of the drainage member 31 and the leakage moisture in the arrangement shown in the first embodiment and the arrangement shown in Figs. 6 and 7 is thus safely conducted laterally of the wall to be protected and the leakage moisture does not therefore pass downwardly on the top of the wall to cause deterioration thereof.

While the invention has been described with reference to specific structural details concerning the general over all shape of the coping sections it will be appreciated that changes may be made in the design thereof. Such changes and alterations in the shape of the drain member may be made without departing from the spirit and scope of the invention as set forth in the appended claims.

I claim:

1. A wall coping unit comprising, coping sections having substantially straight end portions arranged adjacent each other, moisture resistant means filling a space between adjacent ends of

30 the coping sections, means arranged transversely of the coping sections immediately under said adjacent ends for draining moisture penetrating through said space laterally of the coping sections, and means carried by said coping sections 35 maintaining said means transversely of the coping sections and under the adjacent end thereof.

2. A wall coping assembly comprising, coping sections arranged with ends thereof adjacent each other to provide joints between the ends 40 of the coping sections, drainage means arranged transversely of the coping sections immediately under said joints for conducting moisture penetrating between adjacent ends of said coping sections laterally of the wall, and means carried by the coping sections maintaining said drainage means under said joints.

3. A wall coping assembly comprising, coping sections arranged with ends thereof adjacent each other to provide joints between the ends 50 of the coping sections, a drainage member extending transversely of the wall under adjacent ends of the coping sections, said member having a channel therein for conveying moisture penetrating through said joints laterally of the wall, and means integral with said coping sections holding said drainage member in said transverse position.

4. A wall coping assembly comprising, coping sections covering the wall and arranged therealong with ends of the coping sections adjacent each other providing a space between ends of the coping sections, a drainage member extending transversely of the coping sections under adjacent ends thereof, means carried by said drainage member closing said space, sealing means filling said space, means carried by said drainage member for conducting moisture passing through said space laterally of said wall, and means maintaining the first mentioned means in position to close said space.

5. A wall coping assembly comprising, coping sections covering the wall and arranged therealong with ends of the coping sections adjacent each other providing a space between ends of the

coping sections, a drainage member extending transversely of the coping sections under adjacent ends thereof, a rib carried by said drainage member closing said space, sealing means filling said space, and a drainage member having channels therein adjacent said rib for conducting moisture passing through said space laterally of said wall.

6. A wall coping assembly comprising, coping sections covering the wall and arranged therealong with ends of the coping sections adjacent each other providing a space between ends of the coping sections, spaced depending ribs carried by the coping sections terminating short of the ends thereof for supporting the coping sections on the wall, a drainage member arranged transversely of the coping sections under adjacent ends thereof and intermediate ends of said ribs, a rib carried by the drainage member closing the space between adjacent ends of the coping sections, sealing means filling said space, and means carried by the drainage member for conducting moisture passing between adjacent ends of the coping sections laterally of said wall.

7. A wall coping assembly comprising, coping sections covering the wall and arranged therealong with ends of the coping sections adjacent each other providing a space between ends of the coping sections, spaced depending ribs carried by the coping sections terminating short of the ends thereof for supporting the coping sections on the wall, a drainage member arranged transversely of the coping sections under adjacent ends thereof and intermediate ends of said ribs, means securing said drainage member to said wall, a rib carried by the drainage member closing the space between adjacent ends of the coping sections, sealing means filling said space, and said drainage member having channels therein for conducting moisture passing between adjacent ends of the coping sections laterally of said wall.

8. A wall coping assembly comprising, coping sections arranged over the wall with ends thereof adjacent each other providing a joint between ends of the coping sections, spaced depending ribs carried by said coping sections for supporting the coping sections on the wall, said ribs having recessed shoulders adjacent ends of the coping sections, and a drainage member extending transversely of said coping sections under adjacent ends thereof and supported on the recessed shoulders of said ribs for conducting moisture penetrating through the joints between the ends of the coping sections laterally of said wall.

9. A wall coping assembly comprising, coping sections arranged over the wall with ends thereof adjacent each other providing a joint between ends of the coping sections, spaced depending ribs carried by said coping sections for supporting the coping sections on the wall, said ribs having recessed shoulders adjacent ends of the coping sections, and a sheet metal drainage member extending transversely of said coping sections immediately under adjacent ends thereof and supported on the recessed shoulders of said ribs for conducting moisture penetrating through the joints between the ends of the coping sections laterally of said wall.

10. A wall coping assembly comprising, coping sections arranged with ends thereof adjacent each other to provide a joint between the ends of the coping sections, a relatively narrow drainage member of greater length than the width of the wall arranged transversely of the wall under the adjacent ends of the coping sections, said member having a channel therein for conveying moisture penetrating through said point laterally of the wall, and means for maintaining said drainage member in a transverse position under the adjacent ends of the coping sections.

MARTIN S. BOWNE.
